UNITED STATES PATENT OFFICE.

ELMER J. GASS AND DAVID W. THURSTON, OF PITTSBURGH, PENNSYLVANIA.

UNLOADING DEVICE.

1,416,190.

Specification of Letters Patent.

Patented May 16, 1922.

Application filed May 31, 1919. Serial No. 300,933.

To all whom it may concern:

Be it known that we, ELMER J. GASS and DAVID W. THURSTON, both citizens of the United States, residing at Pittsburgh, Allegheny County, Pennsylvania, have invented a new and useful Improvement in Unloading Devices, of which the following is a full, clear, and exact description, reference being had to the accompanying drawings, forming part of this specification.

This invention relates to an improvement in unloading devices and is more particularly designed for unloading cars containing material to be wasted, or fill material such as slag or cinders for grading railroads, etc.

The object of our invention is to provide an efficient device of this character which is arranged to be moved over the tracks of a railroad and which is provided with rails mounted thereon arranged to be connected with the railroad tracks, the arrangement being such that the cars of fill material can be moved from the railroad to the track on the unloading device. The unloading device is provided with one or more hoppers for receiving the material from the cars, and is also provided with a conveyor for conveying the material from the unloading device transversely with relation to the tracks to a suitable distance therefrom.

The precise nature of our invention will be best understood by reference to the accompanying drawings which will now be described, it being premised, however, that various changes may be made in the details of construction and the general arrangement of the parts without departing from the spirit and scope of our invention as defined in the appended claims.

Figure 1 of the drawings is a side elevation of a portion of our improved unloading or fill handling machine.

Figure 1^a is a similar view of the other portion thereof.

Figure 2 is a plan view.

Figure 3 is an end view partially in section with the ramp or inclined track removed.

Figure 4 is a plan view of a fill-receiving hopper.

Figure 5 is a longitudinal section through the hopper shown in Figure 4, and in which we have shown a plurality of adjustable baffle plates, and

Figure 6 is an end view of a modified form of machine.

Referring to Figures 1 to 4 of the drawings, the reference character 2 designates trucks at each end of the machine having longitudinal sills 3; and 4 car wheels mounted on suitable axles, which are journaled in suitable bearings which are connected to the longitudinal sills 3. Connected to the longitudinal sills 3 of the trucks 2, by means such as a pin and slot 3' permitting relative movement, are intermediate longitudinal sills 5, which are on a lower plane than the sills 3 and mounted on the sills 3 and 5 are cross ties 6. The cross ties on the sills 5 are in a lower plane than the ties on the sills 3, and supported on the cross ties on the sills 5 are stringers 7 which, together with the cross ties on the sills 3, are arranged to support longitudinally extending rails 8. These rails 8 extend from end to end of the structure and are connected to the rails 9 of a railroad track on which the wheels 4 of the device are mounted, by means of rails 10, supported on inclined stringers 11. The ends of these stringers 11 adjacent to the unloading machine are supported on transverse beams 12' on the trucks.

Supported on the frame work of the unloading machine are transversely arranged hoppers 12 closed at one end, as indicated at 13 in Figure 4. These hoppers are provided with openings 14^a for the reception of the stringers 7. Extending transversely from the unloading machine are boom members 14, which are connected to the frame work of the unloading machine and are also supported by means of guy rods 15, arranged to support the outer ends thereof. These boom members are also connected to each other by means of vertical struts 16 and angular brace members 17.

In the drawings we have shown two hoppers and two boom structures in connection with the unloading machine, which are so spaced with relation to each other that the hoppers will be positioned under the two drop gates of coal cars of the usual pattern, or cars of a similar type. We desire it to be understood, however, that the structure may be of sufficient length and may be provided with sufficient hoppers to unload a plurality of cars simultaneously.

Mounted in pairs on the boom members

2
 14 are a series of rollers 18, which are arranged to support an endless carrier 19, which passes over a driving pulley 20 at the outer end of the boom structure, and a pulley 21 at the other end thereof. The pulley 21 is mounted on a shaft which is journaled in adjustable bearings and which are adapted to be adjusted by means of the take-up device 22, in order to take up the slack in 10 the conveyor. Secured to the shaft on each of the pulleys 20 is a driving pulley 23, which is connected by means of a belt 24 with a pulley 25 on a shaft 26. The shaft 26 is connected to a driving motor 27 by 15 means of a universal coupling 28, and 29 is a similar coupling in said shaft between the pulleys 25 arranged to drive the adjacent conveyors, as clearly shown in Figure 2.

20 Connected to the boom members 14 and on each side of each of the conveyor belts are metallic strips 30 which form guides for the material moved along on the conveyors 19. These strips are made up of sections, a number of which are arranged to be swung at an angle to the conveyor as indicated in chain lines at 31, in order to scrape the material from the conveyor before it reaches the end of the boom structure.

25 30 Extending longitudinally of the unloading device and transversely with relation to the hoppers and within each of the hoppers, as clearly shown in Figure 3, are a plurality of baffle plates 32, which are arranged to 35 support a portion of the load of the material dumped from the cars to prevent overloading the conveyor. These baffle plates may be formed integral with the structure, as shown in Figure 3 of the drawings, or 40 may be arranged to be adjusted to different inclinations by the lever mechanism shown at 33 in Figure 5 of the drawings. Cars such as shown at 35 in Figures 1 and 3 of the drawings are run onto the rails 8 of the 45 device, as indicated in the drawings, and the drop gates are then opened to permit the material to fall from the car into the hoppers, which material is transferred from the hoppers outboard by means of the endless 50 conveyors which are continuously driven by means of a motor 27. If all of the members such as shown at 31, are parallel with the endless conveyor, the material will be conveyed to the end of the boom structure 55 from which it will fall by gravity, but if any of the sections 31 are placed at an angular position the material will be scraped from the conveyors.

60 By providing baffles such as 32, the danger of clogging the machine by overloading the conveyors, is avoided if the drop gates over the hoppers should be suddenly opened to permit a large quantity of material to fall from the car.

65 In Figure 6 of the drawings we have

shown a structure similar to that shown in the other figures and in which we have used the same reference characters with the letter "a" affixed for designating similar parts. In this construction we have shown an upwardly extending frame work 36 on each side of the structure, which frame work is connected by transverse beams 37 above the line of the top of the cars. The boom structures in this case are formed of two members which are hinged to each other at 38 and instead of supporting the beam structures by means of guy rods, they are supported by means of a cable or cables 39, which pass over sheaves 40 to a winding drum 41. By means of the winding drum and the supporting cables we are able to raise and lower the outer end of the boom members, together with the one end of the conveyor in order to enable us to increase the height of the fill, if desired, and also to lower the boom structure when first starting the fill, which will reduce the work required for driving the conveyors. By means of this structure, we are also enabled to raise the boom structure into a vertical position so that the same will be out of the road when moving the structure, and which will also permit the structure to pass obstructions along the track. The transverse timbers 37 also form a platform on which the workmen can stand for manipulating the bars or rods when loosening the material in the car being dumped.

65 It will be readily understood by those familiar with the art that the motor 27 may be provided with suitable connections for actuating the drum 41 and it may also be connected so as to actuate a drum or windlass for moving the cars from the main rails 9 to the rails 8 on the structure, as well as for moving the machine along the track.

The inclined tracks are supported on the ends of the unloading device and the railroad track, but these inclined tracks can readily be removed and placed on the device or on suitable cars when moving the structure from place to place.

70 The advantages of our invention result from the provision of an unloading device supported on the rails of a railroad track, and which is also provided with a track thereon, together with an inclined track connecting the track on the unloading device with the main track so that the cars to be unloaded can be moved from the main track up the inclined track onto the track on the unloading device. Furthermore, from the provision of a conveyor mechanism for conveying the material from suitable receptacles on the unloading device outboard from the unloading device.

75 We claim:

1. An unloading device, comprising a truck having a plurality of independent

longitudinally extending sills, means connecting said sills and permitting relative movement therebetween, a hopper mounted on certain of said sills, and a conveyor below said hopper, substantially as described.

2. An unloading device, comprising a truck having a plurality of independent longitudinally extending sills, a lost motion connection between certain of said sills, a hopper mounted on certain of said sills, and a conveyor below said hopper, substantially as described.

3. An unloading device, comprising a truck having a plurality of independent longitudinally extending sills lying in different horizontal planes with the sills adjacent the opposite ends of the truck being above the intermediate sills, a hopper supported by said intermediate sills, cross-ties on the intermediate sills, stringers mounted on said cross-ties, a hopper on said truck, said hopper having openings for the passage of said stringers, and a conveyor below said hopper, substantially as described.

25 4. An unloading device, comprising a truck having a plurality of independent longitudinally extending sills lying in different horizontal planes with the sills adjacent

the opposite ends of the truck being above the intermediate sills, a hopper supported by 30 said intermediate sills, cross-ties on the intermediate sills, stringers mounted on said cross-ties, a hopper on said truck and a conveyor below said hopper, substantially as described.

35 5. An unloading device, comprising a truck having a plurality of independent longitudinally extending sills lying in different horizontal planes, a hopper mounted on the sills lying in the lowermost plane, a conveyor below said hopper, and tracks above the hopper carried by the sills in the uppermost plane, substantially as described.

6. An unloading device, comprising a truck having a plurality of independent 45 longitudinally extending sills lying in different horizontal planes, the sills adjacent the opposite ends of the truck being above the intermediate sills, a hopper supported by said intermediate sills, and a conveyor below 50 said hopper, substantially as described.

In testimony whereof, we have hereunto set our hands.

ELMER J. GASS.
DAVID W. THURSTON.
